(57) **CLAIM**

The ornamental design for a pool safety frame, as shown and described.

DESCRIPTION

FIG. 1 is a top perspective view of a first embodiment of a pool safety frame showing our new design;

FIG. 2 is a left side view of the first embodiment of the pool safety frame;

FIG. 3 is a top view of the first embodiment of the pool safety frame;

FIG. 4 is a top perspective view of the first embodiment of the pool safety frame in use;

FIG. 5 is a top perspective view of a second embodiment of a pool safety frame;

FIG. 6 is a left side view of the second embodiment of the pool safety frame;

FIG. 7 is a top view of the second embodiment of the pool safety frame; and,

FIG. 8 is a top perspective view of the second embodiment of the pool safety frame in use.

Right side views, front views and rear views of the first and second embodiments not shown are mirror images of the left side view. Bottom views not shown are mirror images of top views.

Any broken lines illustrative of environmental structure in the drawings are not part of the design sought to be patented.

1 Claim, 6 Drawing Sheets
